AMUSEMENT DEVICE

Carl Edward Lundberg, Walden, N. Y., assignor
of one-half to Harry C. Baker, Larchmont,
N. Y.

Application December 17, 1931
Serial No. 581,590

9 Claims. (Cl. 272—43)

This invention relates to amusement devices used in fairs, carnivals, etc., and more particularly to that type of amusement devices in which a number of carriages are rotated around a common center to provide amusement for passengers in the carriages.

A particular object of this invention is to provide a novel mechanism by which a number of carriages are simultaneously subjected to a novel series of motions while said carriages are traveling around a common center.

A further object of this invention is to provide a mechanism of this character which shall be simple but substantial in design and safe in operation.

Other objects of the invention are shown in the specification and drawings in which Fig. 1 is a plan view of my amusement device.

Fig. 2 is a partial plan view of same, with the rotating platform and carriage mechanism removed.

Fig. 3 is a vertical sectional view of my amusement device on line 3—3 of Fig. 1.

Fig. 4 is a vertical sectional view of a swivel bearing on line 4—4 of Fig. 5.

Fig. 5 is a plan view of the swivel bearing of Fig. 4.

Fig. 6 is a plan view of a pivot bearing.

Fig. 7 is a vertical sectional view of said pivot bearing on line 7—7 of Fig. 6.

Fig. 8 is an enlarged sectional view of the driving mechanism of my amusement device.

Fig. 9 is a side view of a tie rod support.

Fig. 10 is a vertical sectional view of a part of the stationary platform on line 10—10 Fig. 1, showing a modification of its top surface.

Throughout the views the same reference numerals apply to corresponding parts.

Referring to the drawings, 15 is a circular stationary platform, preferably made of wooden boards or beams 16 of wedge shaped contour, mounted on respective inner and outer circular, laminated sills 17, 18, by means of bolts or other suitable appliances.

Sills 17, 18 form a sub-unit with platform 15 and said sub-unit rests on posts or pillars 19, the parts being secured by means of bolts and brackets 21 or other suitable means, so as to prevent the same from shifting.

Posts 19 which may either be made of concrete, steel, or wood, are anchored in the earth or ground 20.

The top surface of platform 15 is partly covered with an annular sheet metal plate 22, which can be built in sections if so desired.

To the inner circular edge 23 of platform 15 are

secured a suitable number of roller-carrying brackets 24 which carry rollers 25. These rollers 25 engage the rim 29 and thereby center the turntable 35. The number of rollers 25 to be used may vary. It is merely essential that the turntable 35 be maintained in proper position at all times by said rollers.

A rail support 28 is connected to posts 26 by means of brackets 27. This track support is preferably made of wooden boards or beams, and it has on its top surface two circular metal rails 30, 31 which are held to track support 28 by spikes 32.

A suitable number of rollers 33, held in brackets 34 which are connected to the lower surface of an annular turn table 35, permit the latter to freely rotate on said metal rails.

An angle iron 29 is connected to the outer cylindrical surface of said turntable and one leg of said angle iron is below and abuts the bottoms of rollers 25. This prevents turntable 35 from rising and leaving rails 30, 31.

A circular rack or gear 60 is connected to the bottom surface of the turn table, and said rack 40 meshes with a gear 61, mounted on shaft 62. The shaft is mounted in two bearings 63, 64 which are connected to the bottom surface of one or more beams.

Shaft 62 is driven by a motor 65 of any suitable type. This motor, which here is shown located at the outer circumference of the amusement device, may of course be located underneath the platform if so desired.

I have here shown a circular rack and gear drive, but it is understood that I do not limit myself to this particular manner of operating the turn table and that I may also employ a chain, belt, cable, worm or any other kind of driving mechanism to suit the conditions and requirements which may arise.

Spaced from the common centre of the turn table and stationary platform, is a base shaft or pivot member 36, held vertically in a pillar 37 which is located in ground 20. Rotatably held to said pivot member 36 is a pivot bearing 38, composed of two circular discs 40, kept separated by circularly disposed posts 39 and trunnions 41 secured to said plates. A sleeve or bushing 42 riveted or welded to one or both of said plates in the centre thereof, furnishes a long anti-wear bearing surface for pivot member 36. A collar 43 is connected to the pivot member 36 above the top plate 40. While I have here shown a sleeve bearing, it is understood that roller or ball bearings may also be substituted therefor, if so de-

100
105
110

sired. It is to be observed that the base shaft 36 is foreshortened at its upper end as shown in Fig. 3, and therefore may be extended upwardly to form a supporting means for a canopy or other cover (not shown). This shaft, 36 has a straight uninterrupted vertical axis and as such is well adapted to be a suitable support for the purpose above indicated.

Trunnions 41 are connected to carriage rods 10 45, which are free to swivel, and said rods 45 extend in a radial direction from the pivot bearing. To the outer ends of said rods are secured amusement carriages 46 of a type commonly used in connection with amusement devices of 15 the character here described.

Each carriage is provided with a safety strap 47. Each carriage is further provided with a projection 48, which is connected with the rod 45 by means of a pivot member 49.

20 Near the outer edge and on the top of turn table 35 are provided swivel bearings 50. These locate and support carriage rods 45. Each bearing consists of a base plate 51, bolted to the turn table and a circular swivel plate 52, held freely turnable on said base plate by means of a rod 53 which is secured to the base plate. Two uprights 54, preferably made of channel iron, are welded on or may be riveted or bolted to swivel plate 52 and have on their upper flanges a top plate 55 30 with a stud or pin 66 in its centre.

A roller 67 held between uprights 54 and rotatable on a rod or bolt 68, supports carriage rod 45 and provides an anti-friction bearing.

Near the outer edge of the turn table and between swivel bearings 50 are secured tie rod supports 70, which support tie rods 71, which are connected to supports 70 by members 72 and to pins 66 on swivel bearings 50. This arrangement provides a strong and rigid reinforcement of the 40 swivel bearings.

The top surface of stationary platform 15 with sheet metal plate 22 is shown to be planar in Fig. 1. It is however possible to provide this top surface with curvatures of wave like nature, as 45 shown in Fig. 10, in which a sheet metal plate 74 is shown secured to a curved top surface of a platform 75.

During the turning of turn table 35, carriage rods 45 passing through swivel bearings 50 are 50 forced to move with said table. Due to the eccentric location of pivot bearing 38, the rods 45 slide to and fro in swivel bearings 50, so that the carriages at the ends of said rods turn back and forth on the stationary platform. The carriages 55 46 are mounted on rollers, as shown in Fig. 3, so that they move in unison with rods 45. The change of leverage during motion and the oscillating movement of the carriages, as well as a slight radial displacement of the rods will 60 cause the carriages to move in a circle at the ends of said rods, thus causing a variety of motions for the amusement of the occupants of the carriages.

If so desired an additional up and down motion 65 of the carriages may be provided, by making the top surface of the platform wave-like as shown in Fig. 10. Rods 45 will thus be subjected simultaneously to an up and down motion in bearing 50. To provide for this, it is necessary 70 to increase the space between roller 67 and top plate 55.

While I have shown six carriages on the present device, it is of course understood that their number may be varied to suit any conditions and 75 requirements. It will be apparent, that this in-

vention is capable of various modifications without departing from the spirit of the invention.

The appended claims are therefore intended to include such modifications of the invention as would occur to one skilled in the art to which the 80 invention relates.

I claim:

1. In an amusement device the sub-structure including a stationary platform having its central portion cut away, a central rotary turntable located in said cutaway portion, a bearing rim on said turntable located on the circumference thereof, said stationary platform having centering means for said turntable engaging the bearing rim thereof, said turntable having a large central aperture, a vertical shaft located in spaced relation eccentrically of said aperture and turntable, said shaft having a straight uninterrupted vertical axis, a bearing mounted on said shaft above said turntable, rods articulately connected to said shaft bearing and slidably passing through swiveled retainers, said retainers being secured to the edge of the turntable and extending upwardly therefrom, means to propel the turntable rods and swivels and thereby propel the shaft bearing about said shaft through the medium of said articulate connections with said rods.

2. In an amusement device, the sub-structure, including two concentric members comprising a stationary platform having undulations defining portions of the upper surface thereof and a turntable, said platform having a cutaway portion centrally located, the turntable being located in said cutaway portion, cooperating centering means on said members to center said turntable within said platform, said turntable member having a large central opening, a vertical shaft located eccentrically in said opening and to said turntable, said shaft having a straight uninterrupted vertical axis, a bearing located on said shaft above said turntable, rods articulately connected to said bearing and slidably supported in swivels secured to the edge portion of the turntable and extending upwardly therefrom, vehicles pivotally attached to the free ends of said rods and traversing the undulations of said stationary platform, means on said swivels to prevent displacement of said rods from said swivels as the vehicles ride over the crests of said undulations on said stationary platform, means to drive said turntable, said rods, vehicles and swivels, whereby the shaft bearing is propelled about the shaft by said rods.

3. In an amusement device, a stationary platform having a circular hole centrally located therein, a metal covering on the surface of said platform, a turntable located in the circular hole of said platform cooperating means on said platform and turntable to maintain the turntable accurately centered in said platform, said turntable having a large centrally located hole therein, a base shaft located eccentrically of said last named hole and extending vertically therethrough, said shaft having a straight uninterrupted axis whereby said shaft may be extended upwardly to form a support, said shaft carrying a rotatably mounted hub, carriage rods radially disposed from and pivotally connected to said hub, said rods passing slidably through swiveled guides located and pivotally connected to the edge portion of said turntable, amusement carriages on said metal covering, each one of said carriages being articulately connected respectively to the free ends of said rods and means to

- actuate said turntable and thereby propel said rods, carriages and hub about said base shaft and thereby to impart to said carriages a variety of amusing motions.
- 5 4. In an amusement device, a stationary platform having a central opening therein, a turntable located within said opening and centered therein by cooperating centering means said turntable having a large central hole, a base shaft 80
10 passing eccentrically through said hole, and spaced therefrom said shaft having a straight uninterrupted axis whereby it may be extended vertically to form a support, a hub rotatably mounted on said shaft, carriage rods radially disposed from 85
15 and articulately connected to said hub, swivelled supports pivotally mounted on the edge portion of said turntable, said rods passing slidably and individually through their respective support, an amusement carriage articulately connected to the
20 free end of each rod and movably resting on said platform, tie rod supports secured on the edge portion of said turntable and located intermediate said swivelled supports, tie rods secured to and extending from said tie rod supports to the upper 90
25 ends respectively of said swivelled supports and journaled to said swivelled supports, whereby said swivelled supports are amply braced and maintained in vertical position, and means to actuate said turntable and thereby propel said rods, carriages, and hub about said base shaft and imparting 95
30 to said carriages a variety of amusing motions.
5. In an amusement device, the substructure comprising a guide adapted to be swivelly mounted on the edge portion of a rotary turntable, said 100
35 guide having horizontal upper and lower plates connected by side plates, antifriction means supported horizontally by said side plates, a tie rod journal extending upwardly from the upper plate and a swivel bolt extending downwardly from 105
40 said lower plate substantially as described.
6. In an amusement device, the substructure including a rotary turntable having guides swivelly mounted on the edge portion thereof, said guides having horizontal upper and lower plates connected by side plates, antifriction means supported by the side plates, a journal on the upper plate and extending upwardly therefrom, supporting posts secured on the edge portion of said turntable intermediate said swivelled guides, tie rods engaging said journals and connecting 110
45 said swivelled guides and said supporting posts whereby said swivelled guides are braced to prevent vertical tilting.
7. In an amusement device, the substructure, including a stationary platform having a central cutaway portion, a rotary turntable located in said platform, said turntable having a large central opening and a bearing rim on the circumferential edge of said turntable, rollers secured to said platform and engaging said rim for centering said turntable in said platform.
8. In an amusement device, the substructure, including a stationary platform having a central cutaway portion, a rotary turntable located in said cutaway portion, said turntable having 115
50 a large central opening and a bearing rim secured circumferentially to said turntable, rollers secured to the platform and engaging said rim for centering said turntable, said rim having an outwardly extending flange engaging the lower portions of said rollers to prevent upward displacement of said turntable relative to said platform.
9. In an amusement device, according to claim 7 in which the platform and turntable are provided with cooperating means to prevent upward displacement of said turntable relative to said platform substantially as described.
